UNITED STATES PATENT OFFICE.

ANGUS L. McTAGGART, OF PITTSBURGH, PENNSYLVANIA.

PARALLEL-RULER.

1,322,592.

Specification of Letters Patent. Patented Nov. 25, 1919.

Application filed February 24, 1917. Serial No. 150,786.

To all whom it may concern:

Be it known that I, ANGUS L. McTAGGART, a subject of the King of England, residing at Pittsburgh, in the county of Allegheny 5 and State of Pennsylvania, have invented certain new and useful Improvements in Parallel-Rulers, of which the following is a specification.

The principal objects of my invention are 10 to provide a simple and efficient parallel motion ruler to enable straight and parallel lines to be readily produced; a ruler positive in its action and easily operated; a ruler having clamping or locking means designed 15 to fixedly position the straight-edge of the ruler in any desired position throughout its length of travel; and a ruler constructed to permit the use of a continuous length of drawing paper and to prevent contact of the 20 straight-edge with drawing paper during the travel of the edge over the paper.

In the accompanying drawing, which illustrates an application of my invention,

Figure 1 is a plan view, broken away at 25 the center of a parallel ruler embodying my invention.

Fig. 2 is an end elevational view.

Fig. 3 is a sectional view taken on line 3—3 of Fig. 1.

30 Fig. 4 is a detail sectional view, the section being taken on line 4—4 of Fig. 3.

Referring to the drawing, my parallel-ruler is designed to be used in connection with a suitable table or drawing-board 1, and 35 is operable on a track elevated a slight distance from the board. As illustrated and as preferred, the track comprises two rack-bars 3 secured to the board in parallel relation by means of screws 4 passed through 40 the rack-bars and through apertured spacing members 5. The purpose of the members 5 is to provide a desired space between the board and the under face *a* of each rack-bar, a space sufficient to permit travel of the 45 straight-edge 6 between said racks and the board and also sufficient to permit the drawing paper to be inserted between the board and the under face of the straight-edge. By this construction it will be noted that a continuous piece of drawing paper may be employed or a sheet of any desired length 50 easily manipulated.

The straight-edge 6 is supported and carried throughout its travel by a suitable 55 traveling and carrying means arranged to be moved throughout the length of the

track. As illustrated, these means include a pair of housings or blocks 7 each being disposed adjacent to the respective rack-bars, a rotatable shaft 8 journaled in ball or other suitable bearings 9 mounted in the blocks 7; pinions 10, one fixed on each end of shaft 8, and ring members 11, the latter being rigidly secured to shaft 8 and adapted to revolve therewith. The straight-edge 6 60 extends from one block to the other and slightly beyond the block a sufficient distance to engage the face *a* of the respective rack-bars. Said straight-edge is secured adjacent its ends to the bottom faces of the blocks by 65 means of counter-sunk bolts 12 and nuts 13, the former being passed through the straight-edge and a portion of the block and terminating in recesses 14 formed in the 70 blocks.

75 15 designates a pair of thumb screws, each being adapted to coöperate with one of the rotatable rings 11, for the purpose of locking the straight-edge at any desired point within the length of its travel on the track.

80 What I claim is:

1. In a parallel ruler, the combination with a table or board, of a pair of spaced-apart parallel rack-bars, means for spacing the under faces of said bars away from 85 the table or board, a straight-edge having end portions extending under the rack-bars, a rotatable shaft having pinions thereon co-operating with the rack-bars, movable blocks through which the ends of the shaft 90 project, shaft bearings in the blocks, a ring fixedly mounted on the shaft within a block, locking means coöperating with the ring, and means for securing the straight edge to the blocks.

95 2. In a parallel ruler, the combination with a table or board, of a pair of spaced-apart parallel rack-bars, means for spacing the under faces of said bars away from the table or board to permit drawing paper 100 to be inserted between the board and the under faces of said rack-bars, a straight-edge, a rotatable shaft having pinions thereon coöperating with the rack-bars, blocks through which the ends of the shaft project, 105 shaft bearings in the blocks, a ring fixedly mounted on the shaft within a block, locking means coöperating with the ring, said blocks movable with the shaft, and means for securing the straight-edge to the blocks.

110 3. In a parallel ruler, the combination with a table or board, of a track, a support

for the track, means for spacing the track away from its support to permit drawing paper to be passed between the under faces of the track and the board or table, a 5 straight edge, a traveling carrier mechanism mounted on the track, said carrier mechanism including a rotatable shaft, members mounted thereon and engaging the track, and means carried by the shaft to which the 10 straight edge is attached, said latter means including blocks having shaft bearings thereon.

4. In a parallel ruler, the combination with a table or board, of a track comprising 15 spaced-apart parallel elevated rack-bars, a straight-edge having end portions extending under the elevated rack-bars, and a traveling carrier mechanism mounted on the track, said carrier mechanism including 20 a rotatable shaft, pinions rigidly mounted thereon, locking means for preventing travel of the carrier and engaging the rack-bars, and means carried by the shaft to which the straight-edge is attached.
5. In a parallel ruler, the combination with a drawing-board, of a pair of spaced-apart parallel rack-bars secured to said board, means for spacing the under faces of said bars away from the board, a rotatable shaft, 30 blocks carried by the shaft, and disposed adjacent to the rack-bars, pinions on the shaft coöperating with the rack-bars, rings on the shaft and rotatable therewith, said rings each being located within a block, locking 35 means carried by the blocks and coöperating with said rings, a straight-edge secured to

the blocks, said straight-edge extending from one rack-bar to the other and having its end portions arranged to make contact with the under faces of the rack-bars.

6. In a device of the character described, the combination with a drawing-board, of an elevated track secured thereto, means for spacing the under faces of said tracks away from the board, travel means mounted on the track, straight-edge supporting means spaced from the board and carried by the travel means, and a straight-edge secured to its supporting means and spaced from the board, said straight edge having end portions extending under the rack bars.

7. In a device of the character described, the combination with a drawing-board, of an elevated track including a pair of parallel rack-bars secured to the board, means for spacing the under faces of said bars away from the board, travel means including a rotatable shaft having pinions thereon cooperating with the rack-bars, straight-edge supporting means spaced from the board and carried by the travel means, and a straight-edge secured to its supporting means and spaced from the board, and having end portions extending under the rack bars.

In testimony whereof I affix my signature in presence of two witnesses.

ANGUS L. McTAGGART.
